UNITED STATES PATENT OFFICE.

JOSEPH OLMSTED, OF NEW YORK, N. Y., ASSIGNOR TO THE UNITED STATES ELECTRIC LIGHTING COMPANY, OF SAME PLACE.

ELECTRIC LAMP.

SPECIFICATION forming part of Letters Patent No. 252,397, dated January 17, 1882.

Application filed September 7, 1881. (No model.)

To all whom it may concern:

Be it known that I, JOSEPH OLMSTED, of New York, in the county and State of New York, have invented certain new and useful 5 Improvements in Electric Lamps, of which the following is a specification, reference being had to the drawings accompanying and forming a part thereof.

My invention, broadly considered, is an improvement in detent or rack-and-pinion lamps, or those in which the relative position of the carbon pencils is adjusted and controlled through the instrumentality of a magnet or magnets, a movable armature, and a train of wheels, the 15 latter being in gear with one of the carbon-carriers, and controlled in their movement by the magnets.

The lamp which forms the subject of this my present invention is distinguished from others 20 of its class by its extreme simplicity and delicacy of action, the invention being directed mainly to a reduction of the number of the parts hitherto considered necessary to the successful operation of these lamps.

25 In the accompanying drawings, Figure 1 represents in part section the interior mechanism of the lamp; Fig. 2, a plan of the same detached from the lamp, and Fig. 3 a view taken at right angles to Fig. 1 and illustrating the 30 same parts.

Similar letters of reference indicate corresponding parts in the three figures.

The letter A designates the usual metallic frame for supporting the feed-controlling mechanism, which is secured to the upper cross-bar or yoke of the lamp-frame, a portion of which only is shown. In the lower part of said frame A, and rigidly secured to the side thereof, is an electro-magnet with coils of coarse insulated 35 wire. This magnet is indicated by the letter F in Fig. 1, where its means of attachment to the frame are arbitrarily represented by heads or plates of diamagnetic material. The core of soft iron used in the main magnet is extended 40 at right angles to the main portion at either end to form pole-pieces F'. Immediately in front of the aforesaid pole-pieces is a second electro-magnet, E, the coils of which are of fine insulated wire, and the core of which is extended 45 at either end in pole-pieces E', in a simi-

lar manner to that of the main cores F'. Magnet E is supported in standards by pivoting-screws f, so that it may be free to turn upon its horizontal axis and permit the pole-pieces E' to swing in front of pole pieces F'. The 55 movement of the magnet E may be limited by suitable stops when necessary, and there may be employed therewith a spring for opposing the upward movement of the pole-pieces, if so desired. The direction of winding of the coils 60 of said magnet is such as to produce in the pole-pieces a polarity similar to that in the adjacent poles of magnet F.

G is a bar or strip of metal secured to the pole-pieces E', near their ends, in substantially 65 the manner indicated in Fig. 3.

Above the magnets are projections or arms, O, from the side of the frame A, to which, by means of pivoting-screws S, a frame, K, of suitable construction, is pivoted. At one end 70 of said frame is journaled a shaft carrying a pinion, H, and a gear-wheel, C, and near the other end, or at the requisite distance from the first shaft, is journaled a second shaft, R, carrying a pinion which engages with gear-wheel C and a fan, L. The frame K is prevented from tilting below a predetermined point by a stout spring, or simple stop, N, extending from the frame A. 75

D is the carbon-carrier. It is caused to pass 80 through suitable guides in the top and bottom of the frame A, and is provided with a rack, by means of which it meshes with the pinion H.

The operation of the lamp is as follows: The current enters through the main conductor M 85 and passes through the coils of magnet F, from whence it is carried to the lamp frame, to and through the upper carbon, and then to the lower carbon, and off to line. The shunt-circuit (represented by m) conveys a portion of the current through the magnet E; but this latter, being of very high resistance, will be affected only to a slight extent under the normal conditions of arc. Its pole-pieces, therefore, being practically neutral in comparison with pole-pieces F', will be drawn up in line with them. The bar G, being by this means brought up against the wheel C, raises the same and locks it against movement. The carbons are thus separated and the arc formed. As the carbons 90 95 100

are consumed more current is diverted through the coils of magnet E, upon which the pole-pieces begin to exhibit an increasing magnetism and neutralize the attractive effect of magnet F. The weight of the carbon-carrier and its appurtenances causes the pole-piece E' to fall away from the others until the frame K is stopped by detent N. By this means the pressure of the bar G on wheel C is relieved and the latter allowed to turn, its motion being necessarily slow on account of the fan L. These movements are of course so minute as hardly to be perceptible. The above, however, serves to illustrate the principle of action.

15 The above-described lamp is one of great simplicity and effectiveness, and, owing to the small number of parts employed, may be produced at small cost.

What I claim as new, and desire to secure 20 by Letters Patent, is—

1. The combination, in an electric lamp, with the gravitating carbon-carrier, of a swinging frame, one or more gear-wheels carried thereby and meshing with the said carrier, a stationary detent for intercepting the tilting of 25 the frame at a predetermined point, and an elec-

tro-magnet and movable armature in conjunction with one of said wheels, by the action of which the feed and adjustment of the carbons are effected, substantially in the manner hereinbefore set forth. 30

2. The combination, in an electric lamp, with the gravitating carbon-carrier, of a swinging frame, one or more gear-wheels carried thereby and meshing with the said carrier, a stationary detent for intercepting the tilting of the frame at a predetermined point, a magnet in the main circuit, and a pivoted or swinging armature therefor, wound with fine wire, forming a part of a shunt or derived circuit in conjunction with one of said wheels, and by the movement of which, caused by the varying attraction of the magnet, the feed and adjustment of the carbons are effected, substantially in the manner hereinbefore set forth. 35 40

In testimony whereof I have hereunto set my hand this 3d day of September, 1881.

JOSEPH OLMSTED. 45
